Application July 10, 1941, Serial No. 401,876

24 Claims. (Cl. 198—33)

This invention relates to feeding mechanisms and particularly to a feeding mechanism for tapered rollers.

When short tapered rollers, wherein the length of each roller does not greatly exceed its larger diameter, are delivered from a hopper into a feed tube, these rollers not only tend to jam at the entrance of the feed tube, but they may also be delivered either end foremost. In the delivery of tapered rollers to gauging devices and to bearing assembling machines, it is often important that these rollers be delivered successively and rapidly small end first.

It is, therefore, an object of this invention to provide a simple feeding mechanism that will not jam and which will deliver tapered rollers at a controlled rate from a loosely jumbled source of supply to a desired position in stacked end to end supported relation with the smaller ends of the rollers foremost. A further object is to provide a feeding mechanism for delivering articles in a continuous stream from a source of supply and which will temporarily cut off this source of supply whenever these articles being delivered accumulate too fast.

To these ends and also to improve generally upon devices of the character indicated, the invention consists in the various matters herein-after described and claimed. In its broader aspects the invention is not necessarily limited to the specific constructions selected for illustrative purposes in the accompanying drawings in which

Figure 1 is a front elevation with some parts broken away to better illustrate the invention;

Figure 2 is a fragmentary side elevation;

Figure 3 is an exploded view of the feed wheels and associated parts;

Figure 4 is a fragmentary perspective view of the escapement latch in lowest roller supporting position;

Figure 5 is a fragmentary perspective view of the escapement latch in the next to lowest roller supporting position;

Figure 6 is a fragmentary perspective view of the escapement latch operating mechanism and the feed limiting mechanism;

Figure 7 is a fragmentary view showing how a predetermined accumulation of rollers hold the escapement latch in a non-feeding position;

Figure 8 is a fragmentary view of the roller tilting pawl and associated parts;

Figure 9 is a fragmentary perspective view of the hopper feed; and

Figure 10 is a fragmentary sectional view show-

ing how a tapered roller locates small end downwardly between the feeding wheels.

Generally stated, tapered rollers W, placed in jumbled formation in a hopper 10, are directed from this hopper downwardly through a feed tube or guide 12 to an escapement latch generally indicated at 13, which individually and successively releases the tapered rollers into depending laterally supported relation between the inner peripheral edges of a pair of spaced rotating feed wheels 14 and 15 that are arranged to locate these tapered rollers small end downwardly and then deliver them small end foremost into an outlet tube 16. In the event that the rollers W are restricted in their movements from the outlet tube, accumulation of these rollers to a certain point causes one of the rollers to engage a limiting mechanism, generally indicated at 17, which prevents feeding operation of the escapement latch 13 so that delivery of the tapered rollers W to the feed wheels is temporarily stopped until the accumulated rollers again start feeding through the outlet tube 16.

Referring to the illustrated embodiment, an upright tubular post 20, mounted on a suitable base (not shown), has a reduced upper end that receives and supports the lower flanged end 21 of the hopper 10. A bushing 24, secured within the upper end of the post 20 and adjacent to the lower flanged end 21, has a bore 25 aligned with a bore 26 through the bottom of the hopper, and the upper end of the feed tube 12, which is slotted at 27, is supported in the bore 25. In axial alignment with the upper end of the tube 12 is an upper movable tube portion of the same size as the tube 12 and composed of a pair of similar complementary segments 28 which vertically slide within the bores 25 and 26 and which also slidably and longitudinally engage each other. The lower end of each segment 28 has tongues 29 slidably received within the tube slots 27, and the upper ends of the tube 12 and segments 28 are internally rounded at 30 to aid in guiding a roller W past the tube ends. The segments 28 are alternately moved up and down by studs 32 respectively secured at their inner ends to the segments and laterally extending outwardly for vertical movement in vertical slots 33 through the hopper flange 21 and the post 20. Links 34, pivoted at their upper ends to the studs 32, are journalled at their lower ends on the diametrical opposed crank arms 35 and 36 of a crank shaft rotatably mounted in a support 37 fastened on the post 20 and driven by a crank shaft pulley 38 belt-connected to a pulley on a motor 39 fas-

tened to a motor bracket 40 secured to the post 20. In the feeding of successive tapered rollers W endwise into the tube 12, each time that one of the sections 28 is raised and the other section 28 is lowered (Figure 2) one of the rollers W in the bottom of the hopper will slide over the rounded edge 30 of the lower segment and into the tube.

The lower end of the feed tube 12 is fastened in a bore 43 extending downwardly through a terminal block 44 seated on the top face 45 of a laterally projecting generally rectangular portion 46 of an escapement bracket having a foot 47 secured as by screws to the upper portion of a mounting bracket 48 that is fastened on the post 20. This terminal block has locating ears 49 overhanging the top of the projecting portion 46, and thumb nuts and screws co-operatively serve to demountably fasten the terminal block 44 to the escapement bracket so that easy access may be had to rollers W in the lower end of the tube 12 and in the feeding mechanism. A recess 50 is provided between the projecting portion 46 and the foot 47, and a guide chute 51 is secured within this recess to form a grooved partially continuing wall of the tube 12 and which guides the rollers W from the escapement latch 13 into a laterally supported position between the inner spaced peripheral edges of the rotating feed wheels 14 and 15 which serve as a carrier for the rollers. A shaft 52 journalled in the escapement bracket extends across the recess 50 and has a latch block 53 secured thereto for a back and forth escapement rocking movement within the recess 50 towards and from the chute 51 and between the positions of Figures 4 and 5. An escapement plunger 54, slideable within a bore in the latch block 53, has a roller engaging head 55 at its inner end which is urged away from the latch block and towards a roller clamping position by a spring 56 seated within a counterbore in the latch block. A pair of lock nuts on the outer end of the plunger 54 secure it in position and adjustably limit the movement of the head 55 out of the latch block 53.

The latch block rocking movement is controlled by a depending trip lever 58 clamped at its upper end to the shaft 52 and having a lower end which extends downwardly into the path of a series of sleeves 60 rotatable on arcuately spaced pins 61 laterally projecting from the rotating feed wheels 14 and secured at their outer ends to a ring 62. The weight of this trip lever 58 aided by a coiled spring 67 to be later described, tends to normally swing the latch block 53 to the position of Fig. 4 wherein the lowermost roller W of the stack in the feed tube 12 has slid down the chute 51 past the now withdrawn head 55 and into supported engagement on a shoulder 64 in the latch block 53. As the feed wheels 14 and 15 advance in the indicated clockwise direction, the next sleeve 60 engages and swings the bottom of the trip lever 58 upwardly which rocks the latch block 53 towards the position of Fig. 5 whereupon the spring pressed head 55 first yieldably clamps against the supports the next to the bottom roller in the chute 51 after which the further rocking of the latch block to the final position of Fig. 5 withdraws the shoulder 64 from bottom roller supporting engagement so that the bottom roller is released and slides down the chute 51 onto the rotating feed wheels 14 and 15 which are so spaced as to locate and support each roller W small end downwardly as shown in Fig. 10. When a rotatable sleeve 60 75

passes from beneath the trip lever 58, this trip lever again swings downwardly and rocks the latch block 53 back to the position of Fig. 4 wherein the roller W previously supported by the head 55 is released and drops into supported engagement on the shoulder 64, and this results in a corresponding downward feed of the entire stack of rollers thereabove. This back and forth escapement rocking movement of the escapement latch 13 serves to individually and successively deliver the tapered rollers W in spaced relation to the feed wheels 14 and 15 which direct these rollers into a chute 65 from which they enter the outlet tube 16.

The feed wheel 15 is keyed to the end of a shaft 67 rotatably journalled in the mounting bracket 48 and driven by a motor 68 through suitable reduction mechanism including a shaft 69 and intermeshed bevelled gears 72 and 73. This feed wheel 15 is axially located by a cylindrical plug having a portion of reduced diameter seated within this feed wheel bore and held against the end of the shaft 67 by a screw, while a hub portion 74 of enlarged diameter laterally projects from a laterally projecting hub 75 on the feed wheel 15, these hubs 74 and 75 being respectively received within a bore 76 and a counterbore 77 to co-operatively support the feed wheel 14.

Surrounding the counterbore 77 are annularly disposed and peripherally spaced laterally projecting segments 78 each of which presents a flat face in a plane perpendicular to the axis of the feed wheels and opposed to the feed wheel 15. Adjacent to the periphery of the hub 75 for selective engagement with these flat segment faces are uniformly spaced wheel spacers as the three wheel spacers 80 located 120° apart and which generally appear as blocks projecting from the side of the feed wheel 15 towards the feed wheel 14 and having flat segment engaging faces lying in a plane perpendicular to the axis of feed wheel rotation. The segments 78 project laterally through different extents from the feed wheel 14, and each group of segments correspondingly positioned to the uniformly spaced wheel spacers 80 laterally projects to the same extent from the feed wheel 14. These wheel spacers 80 laterally project sufficiently to prevent bottoming of the hub 75 within the counterbore 77. A series of uniformly spaced screws, as the six screws 81 passing through the feed wheel 14, are detachably threaded in the feed wheel 15 so that the feed wheels 14 and 15 may be secured in adjusted spaced relation by prelocating the desired segments 78 against the wheel spacers 80. This precise wheel spacing is desirable so that the machine may be adapted to feeding tapered rollers of different sizes. Also, since the tapered rollers 60 W dropped from the chute 51 onto the feed wheels may land either end uppermost, each of these tapered rollers must be supported by the feed wheels above its center of gravity so that it will of itself turn small end downwardly as shown in Fig. 10.

A stabilizer 84, pivotally secured by a screw 85 to the mounting bracket 48, has an arcuate finger 86 projecting between the upper portions of the feed wheels 14 and 15. Adjustment screws 87 threaded in the outer end of the stabilizer engage the mounting bracket 48 and tiltably position this stabilizer so that a curved upper surface 88 of the finger 86 which extends from beneath the chute 51 in a wheel feeding direction, lies slightly beneath the smaller end of a

roller when this roller is correctly supported by the feed wheels beneath the chute 65. When a tapered roller W lands large end downwardly on the feed wheels 14 and 15, the advance of these feed wheels will tilt the roller so that it will turn over endwise to its small end downward position, and the rocking of this roller after it has turned over will be quickly stopped by the engagement of the periphery of the small roller end against the surface 88 which guides the roller into proper feed wheel supported relation. If desired, sheet metal guards may be placed on each side of the chute 65 in spaced overlying relation to the top portions of the feed wheels to aid the rollers in landing from the chute in proper feed wheel supported relation. These guards are not illustrated as they would obstruct the showing of other mechanism.

A pawl 90, pivoted on a stud 91 in the mounting bracket 48, is arranged to swing towards and from the feed wheels, and is normally gravity-urged downwardly to the position of Fig. 1 wherein an adjustment screw 92 threaded through the pawl rests on a guide plate 94 that is secured to the mounting bracket 48 in front of the feed wheels and which has a curved face 95 that forms the outer wall of the curved upper end of the chute 65. As a taper roller W is advanced by the feed wheels just beyond the finger 86, the upwardly projecting enlarged roller end is first engaged by a screw 96 adjustably projecting downwardly through the pawl and the roller is tilted small end forwardly (Fig. 1), and immediately afterward a depending pawl ear 97 at the entrance to the chute 65 encounters this tilted roller so that the pawl is further tilted to the position of Fig. 8 and the roller is directed small end foremost into the chute 65. This tilting movement is also aided by the roller itself since the center of gravity of the roller which lies well below the feed wheel peripheries tends to initially start each roller tilting in the desired direction as the feed wheel supported rollers are advanced downwardly towards the pawl 90. The escapement latch 13 delivers the tapered rollers W to the feed wheels in sufficiently spaced relation so that after a roller passes the ear 97, the pawl 90 will again drop to the position of Fig. 1 before the next roller is tilted by the screw 96. The screws 92 and 96 are adjustable to accommodate the pawl for tilting rollers of different sizes, and lock nuts secure these screws in their adjusted positions.

A guide block 98 is secured as by screws beneath the guide plate 94 and forwardly of the feed wheels 14 and 15. The lower end of this guide block is bored at 101 to receive the outlet tube 16 secured in position by a set screw. The bore 101 opens into a recess 102 in the lower end of the chute 65 which is provided with a forward vertical wall 103 that forms part of the lower end of the delivery chute 65. This vertical wall aids in directing rollers W into the outlet tube 16 and merges at its upper end with the lower end of the curved face 95 of the chute 65. An elongated guide plate 104, adjustably secured as by a screw 105 at its lower end within the recess 102, extends upwardly between the feed wheels and has an upper curved face merging with a lower vertical face to form a chute wall 106 spaced from the chute walls 95 and 103. The upper side walls of the chute 65 are formed by the spaced feed wheels as indicated in Fig. 1, while the spaced sides of the recess 102 in the guide block 98 aid in laterally guiding the rollers W into the outlet tube 16 after the rollers leave the feed wheels.

Occasionally roller receiving devices, such as gauging mechanisms and bearing assembling devices, to which the outlet end of the outlet tube 16 may be attached, do not accept the rollers as fast as they tend to be normally fed by the escapement latch 13, and this causes the rollers to accumulate in end to end stacked relation in the outlet tube 16 and in the lower end of the chute 65. To prevent clogging of the feed mechanism, when this accumulation of rollers reaches a certain height in the chute 65, the limiting mechanism 17 is restricted in its movement by one of these stacked rollers W to temporarily lock the escapement latch 13 in a non-feeding position until the rollers again start feeding through the outlet tube 16. To accomplish this, a link 110, extending into a latch block recess, is pivoted at one end by a pin 111 to the latch block 53, and is pivotally connected at its other end by a pin 112 to a longitudinally oscillatable slide 113 that is slidable towards and from the escapement latch 13 in a casing 115 having a cover 118. The casing and cover may be fastened to the mounting bracket by screws. A coiled spring 117 within a recess in the casing 115 is compressed against a pin 118 in the slide 113 to resiliently urge the escapement latch 13 towards the position of Fig. 4 and to swing the trip lever 58 downwardly into the path of the sleeves 60, and this spring is sufficiently yieldable to permit the rocking movement of the escapement latch 13 to the position of Fig. 5. The right hand end of the slide 113, as viewed in Figs. 1 and 6, projects beyond the casing 115 and is bored to rigidly receive the upper end of a depending rod 120 secured in vertically adjusted position by a set screw 121. A control member or limit screw 124, adjustably threaded in the lower end of the rod 120 and secured in adjusted position by a locknut, laterally projects freely through a bore 125 in the block 98 for movement into and out of roller obstructing position in the chute 65 under control of the escapement movement of the escapement latch 13. This limit screw is so adjusted that it extends into and obstructs feeding of rollers in the lower end of the chute 65 (Fig. 1) each time that the escapement latch is rocked to its lower roller supporting position shown in Figs. 1, 4 and 6, and a movement of the escapement latch to its upper roller engaging position of Fig. 5 withdraws the limit screw out of the chute 65 and permits a roller to feed past this limit screw into the outlet tube 16.

Whenever rollers W are restricted in their movement from the outlet tube 16 and stack up into the chute 65 to a position adjacent the limit screw 124 as shown in Fig. 7, one of the rollers locates between the limit screw and the chute wall 106 and prevents the normal inward movement of the limit screw 124 past an intermediate position of its stroke to its maximum inward position of Fig. 1. In this roller-engaged position of the limit screw, the slide 113 and link 110 cannot move inwardly far enough to permit the spring-pressed head 55 to withdraw from the roller W supported by this head. Consequently, the feed of rollers past the escapement latch is stopped. While the limit screw 124 remains in the intermediate roller-engaged position of Fig. 7, the latch block 53 lies between the positions of Figs. 4 and 5, and the trip lever 58 is located in the path of the sleeves 60. As each sleeve 60 successively engages the lower end of the trip lever 58 while the rollers W remain stacked into the chute 65 as shown in Fig. 7, the yieldability of the plunger spring 56 permits the latch block 53 to swing to

the position of Fig. 5 while the rollers W are still held by the head 65 in non-feeding relation. Also, each time that the latch block 53 is rocked to the position of Fig. 5, the limit screw 124 is withdrawn from roller engagement and into the bore 125 so that the limit screw engaged roller is periodically released and may drop past the limit screw when the rollers again start feeding into the outlet tube 16. When the limit screw is not restricted in its movement by a roller W in the chute 65, the limiting mechanism 17 again permits the escapement latch 13 to resume its normal roller feeding movement.

We claim:

1. A roller feeding device comprising a pair of spaced members for co-operatively supporting rollers therebetween, means to move said members in unison for transporting said rollers, a guide for receiving a stack of rollers in superposed relation above said spaced members, an escapement latch tiltable back and forth into alternate supporting engagement with the rollers at the two lowest roller positions of said stack, a depending lever secured near its upper end to said latch and gravity-urging the latch into one of its roller supporting positions, and spaced elements movable with one of said spaced members, said elements successively engaging and shifting the lever during the movement of the roller supporting members to intermittently shift the escapement latch to said other roller supporting position whereby rollers will be successively delivered in spaced relation onto the roller supporting members.

2. In a feeding device for rollers, a pair of rotatable members having spaced annular peripheries for co-operatively supporting rollers therebetween, means to rotate said members in unison for transporting rollers, a guide for receiving a stack of rollers in superposed relation above said members, an escapement latch tiltable into alternate supporting engagement with rollers at the two lowest roller positions of said stack, an annular series of spaced elements projecting from one of said rotatable members, a lever secured near its upper end to said escapement latch and having a lower end in the path of movement of said elements, the lever gravity-urging said latch into its lowermost roller supporting position, and said elements successively engaging and releasing the lever during the rotation of the roller supporting members to intermittently shift the escapement latch to its other roller supporting position whereby rollers will be successively delivered in spaced relation onto said peripheries.

3. In a feeding mechanism for rollers, a pair of rotatable feed wheels spaced to laterally support tapered rollers in depending relation therebetween, means guiding a stack of tapered rollers downwardly in end to end supported relation onto said feed wheels, an escapement latch mounted for rocking movement into alternate supporting engagement with the rollers in the two lowest positions of said stack, a downwardly extending lever connected to said escapement latch and urging the latch into one of its roller supporting positions, and spaced pins secured to and laterally extending from one of said feed wheels and operatively engageable with said lever and causing said lever to rock the escapement latch to its other roller supporting position and individually release rollers onto the feed wheels in spaced relation.

4. In a feeding device for tapered rollers, a

pair of feed wheels rotatable about a substantially horizontal axis, spaced inner peripheral edges on said feed wheels for supporting tapered rollers in small end downwardly depending relation therebetween, a discharge chute for receiving the tapered rollers from said feed wheels, means to deliver tapered rollers onto said peripheral edges, mechanism to rotate said feed wheels, a member pivotally mounted above said feed wheels, a depending portion on said member arranged to engage and tiltably direct said feed wheel supported rollers into said chute, and means to adjustably locate the roller engaging position of said member.

15 5. In a feeding device for tapered rollers, a carrier having spaced portions for co-operatively supporting tapered rollers small end downwardly, feeding mechanism for delivering tapered rollers onto said carrier, a roller receiving chute, means to move said carrier to transport the rollers from the feeding mechanism and into said chute, and a member having a plurality of spaced roller engaging portions which successively and co-operatively engage each roller to tilt it into small end forwardly entering relation with said chute.

20 6. In a feeding device for tapered rollers, a pair of spaced feed wheels rotatable about a substantially horizontal axis, said feed wheels being arranged to co-operatively support tapered rollers between their ends and in depending relation therebetween, means to rotate said feed wheels to transport said rollers to a discharge position, a pivotally mounted member above said feed wheels and in the path of the roller transported movement, a plurality of depending portions on said member for tilting the feed wheel supported rollers small end foremost at said discharge position, and means for adjusting at least one of said depending portions towards and from a roller engaging position.

25 7. In a feeding device for tapered rollers, a pair of spaced feed wheels rotatable about a substantially horizontal axis, said feed wheels being arranged to co-operatively support tapered rollers between their ends and in depending relation therebetween, means to rotate said feed wheels to transport said rollers to a discharge position, a pawl pivotally mounted above said feed wheels, a screw adjustably extending from the pawl into the path of the tapered rollers carried by said feed wheels, a depending portion on said pawl engageable with said tapered rollers, said screw and depending portion co-operatively tilting the tapered rollers small end foremost at said discharge position, and means to adjustably position said pawl for controlling the position to which said rollers are tilted.

30 8. In a feeding device for rollers, a pair of spaced feed wheels arranged to receive and support rollers therebetween, means to rotate said feed wheels, a chute for receiving rollers from said feed wheels, feeding mechanism for delivering rollers onto said feed wheels, and a limiting mechanism which renders the feeding movement of said feeding mechanism ineffective in response to an accumulation of rollers in said chute to a predetermined position.

35 9. In a feeding device, an escapement mechanism for feeding articles individually, means to operate said escapement mechanism, an article receiving chute spaced from the escapement mechanism, a carrier for delivering articles from the escapement mechanism and into said chute,

40 75 a control member, means intermittently moving

the control member into and out of the path of articles passing through said chute, and said control member rendering the feeding movement of the escapement mechanism ineffective whenever an accumulation of articles in said chute restricts the movement of said control member into the chute.

10. In a feeding device for rollers, a pair of spaced feed wheels arranged to receive and support rollers therebetween, means to rotate said feed wheels, a chute for receiving rollers from said feed wheels, feed wheel actuated mechanism for delivering rollers onto said feed wheels, and a limiting mechanism responsive to a predetermined accumulation of rollers in said chute for rendering the feeding operation of said feeding mechanism ineffective until said predetermined roller accumulation is diminished.

11. In a feeding device, a feeding tube for receiving articles in stacked formation, an escapement mechanism for releasing articles from said stack, an article receiving chute spaced from the escapement mechanism, means to deliver said articles from the escapement mechanism into said chute, a movable member for engaging one of said articles at a predetermined position in said chute, and a spring urged element in the escapement mechanism and controlled by said movable member to maintain contact with and prevent the release of one of the articles at the lower end of said stack when one of the articles in said chute reaches said predetermined position and restricts the inward movement of said movable member.

12. In a device of the character indicated, a roller feeding mechanism, means to intermittently operate said feeding mechanism, a chute for receiving rollers from said feeding mechanism, a slide operatively connected at one end to said feeding mechanism, a spring engaging the slide and tending to shift the feeding mechanism to a feeding position, a rod rigidly secured to the other end of said slide in depending relation, and a plunger laterally projecting from said rod for movement into and out of the path of the rollers in said chute under control of said feeding mechanism, said plunger engaging a roller in said chute and rendering the feeding movement of the feeding mechanism ineffective whenever rollers accumulate to a predetermined position in said chute.

13. In a device of the character indicated, a pair of rotatably driven feed wheels arranged to receive and transport rollers, a feeding mechanism for discharging rollers onto said feed wheels, a downwardly extending chute for receiving rollers from said feed wheels and having an aperture through one side thereof, means to intermittently operate said feeding mechanism, a slidably mounted member oscillated by said feeding mechanism, a spring engaging said member and tending to shift the feeding mechanism to a feeding position, a downwardly extending rod rigidly secured at its upper end to said member, and a plunger adjustably secured to and laterally projecting from the lower end of said rod into said aperture for movement into and out of said chute under control of the feeding mechanism, said plunger being so adjusted that it will be engaged by a roller in the chute and will render the feeding operation of said feeding mechanism ineffective whenever rollers accumulate in the chute to a predetermined position.

14. In a roller feeding device, a pair of rotat-

able feed wheels arranged to receive and support rollers therebetween, a chute for receiving rollers from said feed wheels, a periodically actuated escapement mechanism for feeding rollers individually onto said feed wheels in spaced relation, a member periodically moved by the escapement mechanism into and out of the path of the rollers in said chute, and said member engaging one of the rollers in said chute and preventing roller feeding by the escapement mechanism whenever said rollers accumulate to a predetermined extent in said chute.

15. In a feeding device for tapered rollers, a pair of spaced feed wheels arranged to laterally support tapered rollers therebetween with each of said rollers directed small end downwardly, a chute for receiving tapered rollers endwise from said wheels, feeding mechanism for individually delivering tapered rollers endwise and in spaced relation onto said feed wheels, means to rotate said feed wheels to transport the tapered rollers from beneath the feeding mechanism and into said chute, and mechanism controlled by one of the tapered rollers in said chute for rendering the feed of said feed mechanism ineffective whenever the tapered rollers accumulate to a predetermined position in said chute.

16. In a feeding device for tapered rollers, a pair of feed wheels rotatable about a substantially horizontal axis, spaced inner peripheral edges on said feed wheels for laterally supporting tapered rollers in small end downwardly depending relation therebetween, feeding mechanism for individually delivering tapered rollers endwise and in spaced relation onto said peripheral edges, a roller receiving chute, mechanism to rotate the feed wheels to transport said tapered rollers from beneath the feeding mechanism into said chute, means successively tilting each feed wheel transported roller so that said tapered rollers enter small end foremost into said chute, and feed mechanism regulating means controlled by an accumulation of tapered rollers in said chute.

17. In a feeding device for tapered rollers, a pair of rotatable feed wheels having spaced peripheral edges arranged to co-operatively support tapered rollers in small end downwardly depending relation therebetween, a feeding mechanism for individually delivering tapered rollers from a source of supply onto said peripheral edges in spaced relation, means to operate the feeding mechanism in timed relation with the feed wheel rotation, a chute for receiving said rollers endwise from said wheels, a member above said feed wheels and tiltably directing each of the feed wheel supported rollers successively and small end foremost into said chute, and a limiting mechanism for rendering the feeding operation of the feeding mechanism ineffective whenever the tapered rollers accumulate to a predetermined position in said chute, said limiting mechanism holding the feed mechanism inoperative only during said accumulation of rollers in the chute.

18. In a feeding device for tapered rollers, a downwardly inclined tube arranged to guide a stack of rollers in end to end supported relation for gravity feeding, a latch block at the lower end of said tube, a shoulder on the lower end of the latch block for releasable engagement with a roller in the lowest position of said stack, a spring pressed plunger movably mounted in the upper end of the latch block and releasably engageable laterally against the roller.

in the next to said lowest position, means to repeatedly rock said latch block back and forth with an escapement movement in such manner that the rollers in the said two lowest positions are successively released, and mechanism arranged to receive the rollers from said latch block and to discharge said rollers endwise with their smaller end directed foremost.

19. In a feeding device for rollers, an inclined chute for guiding a stack of rollers downwardly in end to end supported relation, a latch block mounted for an escapement rocking movement towards and from the two lowest roller positions alternately, mechanism to produce said rocking movement, a shoulder on the lower end of said block for releasably supporting a roller in the lowest position, a plunger slidably mounted in the upper end of said block for movement towards and from said stack to releasably clamp against the next to said lowest roller under control of said latch block rocking movement, a spring urging said plunger towards a yieldable roller engaging position, and means adjustably limiting the plunger movement in the latch block so that the rocking of said latch block presents the plunger in roller supporting engagement just prior to withdrawal of said shoulder to a roller releasing position and said plunger remains in its roller supporting engagement only until the rocking of said latch block initially enters said shoulder into its roller supporting position.

20. In a feeding device for tapered rollers, a pair of rotatable feed wheels, spaced inner peripheral edges on said wheels for co-operatively supporting tapered rollers therebetween in small end downwardly depending relation, and a stabilizing member spaced between said feed wheels and closely beneath the lower ends of said rollers to prevent swinging of said rollers in their feed wheel supported positions.

21. In a feeding device for tapered rollers, a pair of rotatable feed wheels, spaced inner peripheral edges on said wheels for cooperatively supporting tapered rollers therebetween in small end downwardly depending relation, a stabilizing finger having an arcuate roller engaging surface between the feed wheels and below the feed wheel supported rollers, and means to adjustably position said finger so that said roll-

er engaging surface will restrict rocking movement of the feed wheel supported rollers.

22. In a feeding device for rollers, a pair of concentrically mounted rotatable feed wheels, annularly disposed segments in spaced relation laterally projecting through different extents from one of said feed wheels towards the other feed wheel, and spacer members laterally projecting from said other feed wheel for selective engagement with said segments to locate the feed wheels in predetermined laterally spaced relation.

23. In a feeding device for rollers, a pair of coaxially mounted feed wheels, annularly disposed spacer members laterally projecting from one of said feed wheels towards said other feed wheel, said spacer members having outer end faces located in a plane perpendicular to the axis of said feed wheels, a multiplicity of annularly disposed segments laterally projecting in spaced relation and through different extents from said other feed wheel for selective engagement with said spacer members, each group of segments correspondingly positioned to said spacer members having outer end faces located in a plane perpendicular to the axis of said feed wheels, and means to removably secure said wheels together in any of said selectively engaged positions.

24. In a feeding device, a member for guiding a stack of superposed articles downwardly for gravity feeding, a latch block mounted for a repeated escapement rocking movement towards and from the positions of the lowest article and an article higher up in said stack, a shoulder on said block for releasable supporting engagement with an article in said lowest position, an article engaging member yieldably mounted in the latch block above said shoulder for releasable clamping engagement against the article in said higher up position, a gravity-urged lever tending to swing the latch block to one of its article supporting positions, and means successively engageable with said lever for swinging the latch block to its other article supporting position.

GUSTAF ERICKSON.
